UNITED STATES PATENT OFFICE.

NEWTON ANNIS, OF DETROIT, MICHIGAN.

DESIGN FOR A GARMENT-SUPPORTING HOOK.

SPECIFICATION forming part of Design No. 32,777, dated June 5, 1900.

Application filed April 23, 1900. Serial No. 14,055. Term of patent 7 years.

To all whom it may concern:

Be it known that I, NEWTON ANNIS, a citizen of the United States, residing at Detroit, in the county of Wayne and State of Michigan, have invented and produced a certain new and original Design for a Garment-Supporting Hook, of which the following is a specification, reference being had therein to the accompanying drawings, in which—

- 10 Figure 1 is a side elevation of the garment-supporting hook, and Fig. 2 is a perspective view thereof.

In formation the hook comprises a substantially-triangular section A, one side B of which 15 is partly broken away, as shown, and a hook-shaped member C, which rises from the apex

of the triangular section in substantially the same plane with the latter, as illustrated.

The leading feature of my design consists of the triangular section described having extending from its apex a hook-shaped section, the sections being arranged in substantially the same plane.

What I claim as my invention is—

The design for a garment-supporting hook 25 substantially as herein described and shown.

In testimony whereof I affix my signature in presence of two witnesses.

NEWTON ANNIS.
